JESSE M. JENKINS, OF SUMMIT, NEW JERSEY

HAIRPIN

Application filed June 20, 1931. Serial No. 545,713.

This invention relates to improvements in hairpins and particularly one which may be made of a single piece of wire and which is adapted to be inserted into the hair to hold it in place.

It is one of the objects of this invention to provide a hairpin which will be readily inserted into the hair and will be provided with suitable hump portions which so coat with the remaining portion of the hairpin that after the hair is secured within the hump portions of the pin, the pin will be held against accidental dislodgement due to the restricted portions adjacent the hair receiving portions.

It is another object of this invention to provide a hairpin formed from a single piece of wire suitably crimped and made from a resilient material which is less expensive to manufacture and which is more conveniently used than devices heretofore known.

It is another object of this invention to provide a single wire hairpin having a depending central leg portion which restricts the movement of the hairpin except by movement of the resilient prongs whereby the hairpin is prevented from dropping out.

Another object of this invention is to provide a hairpin with a central leg having an enlarged hump portion cooperating with the side prongs to act as a hair controlling latch, other parts of the central leg and side prongs having hump portions coextensive with the humps or crimps in the side prongs to act as hair receiving channels.

Another object of this invention is to provide a hairpin with a resilient guard portion coextensive with a crimped hump portion, which portions are cooperatively formed to secure the hair in appropriate relation and to retain the hair in position.

Another object of this invention is to provide a closed hairpin for adjustably securing the hair, which hairpin is made of a single piece of resilient material and is provided with an overlapping catch to secure the hair within the hairpin except when the catch is released.

Further objects and advantages of this invention will appear from the following de-

scription thereof taken in connection with the attached drawing which illustrates preferred forms of embodiment thereof and in which:

Figure 1 is a plan view of the preferred form of construction of the hairpin. 55

Figure 2 is a side elevation of the hairpin shown in Figure 1.

Figure 3 is a plan view of a slightly modified form of construction of hairpin also showing the central prong. 60

Figure 4 is a still further modified form of construction showing in dotted lines the opened construction, and in full lines the latched position. 65

In the prior constructions of hairpins it has been a principal objective to provide a construction which may be readily inserted into the hair, which will hold the hair in the position in which the hairpin has been inserted, and which will permit ready disengagement of the hairpin when it is desired to be removed. Such a hairpin must be simple in construction and reasonable to manufacture in order to make them commercially practical, but the prior constructions have failed to meet these conditions. 70

The present construction overcomes the failure of such prior hairpins as when the present hairpin is inserted it will stay in the inserted position and will immediately catch. 80

There is no loosening which makes the hairpin objectionably conspicuous and yet the hairpin may be conveniently removed when desired. The particular form of embodiment 85

of this invention shown in Figure 1 shows a one-piece resilient wire hairpin 10 having a plurality of prongs 10a, 10b, and 10c. The center prong 10c is also composed of a plurality of members 11 and 12. The outer prong 90

10a, of the hairpin, which in the drawing is substantially double normal size is provided with a series of humps or crimps which are substantially deep. These humps or crimps extend through the section 13 and at each end develop into straight portions 14 and 15. The prong 10a then curves on itself in a loop 16 to form a parallel portion 17 parallel to the straight portion 15. The portion 17 extends into the inner prong portion 11 which is 95

similarly provided with a plurality of humps or crimps substantially parallel to the humps or crimps 13 in the outer prong 10a. The end crimp 18 in the center prong 10c however 5 extends more closely adjacent the end hump in the section 13 than any of the other humps 11 in the center prong 10c extend with respect to the humps 13 in the outer prong 10a.

This extension of the hump 18 forms an 10 enlarged chamber 18a back of the hump 18 in such a manner that the amount of hair which may be retained within the chamber 18a is many times greater than could easily pass through the restricted channel between 15 the hump 18 and the outer hump or crimp in the section 13 in the side prong and the more hair that is inserted or caught in the chamber 18a, the greater the ratio of obstruction to the hair that can pass the hump 18 which thus 20 acts as an effective barrier to the accidental escape of the hairpin.

The end of the prong 10c comes to a substantial point and forms the unitary connection between the humps 11 and the humps 12 25 in the respective portions of the center prong 10c. The end of the center prong 10c forming the joint extends outward only substantially half the distance of the straight portion 14 in the upper prong 10a and thus falls 30 short of the end of the hairpin 10.

The lower prong 10b is similarly formed with a straight portion 14, hump portions 13, and a second straight portion 15 which loops at 16 into a parallel portion 17 forming the 35 part of the inner prong 10c. The end hump 18 in the adjoining portion of the center prong 10c is similarly closer to the hump 13 than any of the other humps 12 in the center prong 10c. The parallel portions 17 adjacent 40 to the loop portions 16 are preferably welded at 19 in order that the pin as shown in Figure 2 will be in substantially one plane and effectively secured to each other.

In operation, the hairpin 10 having been 45 made of a resilient wire material, will be inserted in the hair and the side prongs 10a and 10b will be resiliently bent about the curved portions 16 with respect to the center prong 10c. The hair will then be caught between 50 the parallel portions 15 and 17 as well as between the parallel hump portions 11 and 13 and 12 and 13. However, due to the closeness of the humps 18 in the center prong 10c with the humps 13 in the outer prongs 10a 55 and 10b, the hair will be effectively caught by the hairpin and as the humps 18 are adjacent the end of the hairpin the hair will not escape but will be effectively caught thus holding the pin in fixed relation. As the hairpin is inserted it will catch all of the hair in the 60 closed end of the hairpin and the tortuous channels between the parallel humps and as there are two separate portions of the hairpin or two separate hair receiving channels between the center prong and each of the side 65

prongs, double the normal amount of hair may be effectively caught by the single pin. The hair will thus be kept in better condition with fewer pins and the pins will not tend to loosen or accidentally drop out.

70

A slightly modified form of construction is shown in Figure 3 in which the hairpin 20 is of the same general construction as the hairpin 10 and similarly has the side prongs 21 and 22 and the center prong 23. The hairpin 20 is made of a single piece of wire and in order to securely retain the adjacent parallel portions 24 and 25 of the center prong 23 the center prong may be twisted at 26. The twisting 26 is in lieu of the spot weld 19 shown in Figure 1, and it is to be understood that other arrangements might be made for holding the parallel portions of the center prong in juxtaposition. It is also to be noted that the end hump in the center prong is similarly closer to the adjacent humps in the side prongs in this Figure than any other humps in the center prong which is similar to the construction shown in Figure 1. The operation of this device is also similar to the 90 device as shown in Figure 1, and when inserted into the hair, the hair will not slip out due to the restricted passage between the enlarged hump. The manufacturing construction is only different although it also 95 provides the plurality of hair receiving channels as shown in the first construction.

95

A further modified form of construction is shown in Figure 4 in which the hairpin 30 is provided with two separate portions 31 and 32. The portion 32 acts as a backing and being substantially smooth and gently curved, more closely adjusts itself to the head of the wearer. The crimped portion 31 has a plurality of crimps 33 forming sharp angles with the back member 32 and providing a plurality of hair receiving compartments 34. The crimped portion 31 is also provided with a sharply curved end 35 which acts as a latch to receive the back portion 32 and secure 110 the hair in the hair receiving compartments.

110

This hairpin is similarly inserted in the hair when the back portion 32 is unlatched and permitted to open as shown along the dotted line. When the hair is received within the compartments 34 the back portion 32 is latched over the hooked end 35 and the hairpin is effectively prevented from coming out. If an unusually large amount of hair is caught within the chamber 34 the end portions 31 and 32 may not be parallel at the end of the hairpin but the latch portion will slide along the back portion a sufficient amount to adapt itself to the hair contained. This is due in part to the resilience 125 of the material and in part to the free sliding relation between the back 32 and the latch 35 which permit the members to adjust themselves according to the supply of hair caught. The latch 35 acts as a securing mem- 130

125

130

ber for preventing the movement of the hair in a manner similar to the enlarged humps 18 and the substantially straight ends 31 and 32 of the respective portions of the hairpin facilitate the insertion of the hairpin into the hair. With such construction the hairpin may thus be easily inserted and retained in the hair and prevented from accidentally dropping out of the hair, although the hairpin may be easily removed when desired.

10 While I have shown preferred forms of embodiment of my device I am aware that other modifications may be made thereto and I therefore desire a broad interpretation of 15 my device within the scope and spirit of the description herein and of the claims appended hereinafter.

I claim:

20 1. A one-piece resilient wire hairpin having a plurality of legs, a hair receiving chamber between said legs, means to restrict and prevent the removal of hair from said hairpin, and a hair receiving chamber adjacent said restricting means adapted to receive a 25 substantial amount of hair.

2. A one-piece resilient hairpin having a pair of opposed legs and a center leg between them, said center leg forming a plurality of cooperating hair receiving chambers, 30 a portion of said opposed legs and said center leg being crimped in substantially parallel relation, said center leg having an enlarged crimped portion extending substantially in contact with said opposed legs and forming a 35 restricted channel for the passage of hair and an enlarged chamber behind the restricted channel whereby the hairpin is prevented from accidental disengagement from the hair.

40 3. A double chamber hairpin comprising a single piece of resilient wire forming a plurality of separate legs and a center leg, a welded portion on said center leg forming an integral hairpin having plural hair receiving chambers, crimped hair receiving portions in said hairpin, an enlarged hair receiving chamber adjacent the end of said hairpin, and an enlarged crimp in said center leg adjacent said enlarged chamber acting as 45 a barrier for the removal of hair from said 50 enlarged chamber.

In testimony whereof I have affixed my signature to this specification.

JESSE M. JENKINS.
